UNITED STATES PATENT OFFICE.

THOMAS N. WALLACE, OF CENTERVILLE, IOWA, ASSIGNOR OF FIFTEEN ONE-HUNDREDTHS TO JOHN R. NEEDHAM, OF CENTERVILLE, IOWA.

PICK FOR MINING OR CUTTING MACHINES.

No. 851,970.

Specification of Letters Patent.

Patented April 30, 1907.

Application filed August 7, 1906. Serial No. 329,519.

To all whom it may concern:

Be it known that I, THOMAS N. WALLACE, a citizen of the United States, residing at Centerville, in the county of Appanoose and State of Iowa; have invented certain new and useful Improvements in Picks for Mining or Cutting Machines, of which the following is a specification, reference being had therein to the accompanying drawings.

10 This invention relates to improvements in mining or cutting machines, and particularly to the pick thereof.

The object of the invention is the novel construction of a pick for a mining or cutting machine, whereby the capacity of the same will be materially increased by the efficient, as well as durable structure of the pick.

15 With this and other objects in view, the invention consists of certain novel constructions, combinations, and arrangements of parts, as will be hereinafter fully described and claimed.

20 In the drawings: Figure 1 is a view in side elevation of a pick constructed in accordance with my invention and showing the same in engagement with the plunger of the mining or cutting machine. Fig. 2 is a top plan view of the pick. Fig. 3 is a transverse, sectional view taken on line 3, 3, of Fig. 1, and 25 looking in the direction of the arrows.

30 The stem 1 of my pick is preferably positioned within sleeve 2 of the plunger 3 of a mining machine. Integral with the stem 1 are side-points 2 and a central-point 3. The 35 side-points 2 are positioned in the same horizontal plane, while the central-point 3 is positioned out of the plane with the side-points 2, thereby placing said point 3 in a higher or lower position with respect to the inverted 40 or upright position, respectively, in which the pick is resting.

45 The central-point 3 is preferably of greater length than the side-points, and the outer end of point 3 is positioned beyond the outer ends of points 2.

50 Each side-point 2 is provided with an outer, flat, vertical side and an inner, beveled side 4, Fig. 3. The central-point 3 is provided with a pair of beveled sides, thereby producing a substantially V-shaped point in cross-section. The two side-points 2 are also substantially V-shaped in cross-section. It is to be noted that all of the points have a cutting edge 5 formed upon the same side of

the pick, whereby a clean cut is made and 55 the points always clear themselves.

A portion of the central and side-points 2 are concaved, thereby producing a longitudinally extending groove 6 upon the bottom or one side of the pick. Among the advantages of this groove may be mentioned the fact that it prevents dirt or coal from clogging around the pick and also relieves friction as to dead space between the two side-points 2.

60 The central-point 3 is a "lead" or performs the function of a "centering device," holding the pick in place, and keeps the same from slipping and losing its power of stroke.

65 My pick may be used on a rotary machine. It is operated preferably by a reciprocating plunger. It is to be noted that, while the central-point will not permit the pick to slip, it will also prevent the same from glancing away from its work.

70 Each point not only tapers throughout its width from the back to the cutting edges 5, but also tapers from the stem 1 throughout its length to the extreme forward end.

75 What I claim is:

1. A pick, comprising a stem, a pair of side-points integral therewith, and a central-point integral with said stem and of greater length than said side-points, said central and side-points provided with cutting edges upon 85 one side thereof and a longitudinally extending groove formed upon the sides of said points opposite to said cutting edges.

80 2. A pick for mining or cutting machines, comprising a stem, a central and side-points 90 integral with said stem, the central point of greater length than said side-points, said side-points positioned in the same horizontal plane, the central-point positioned in a different horizontal plane from said side-points, 95 said side and central-points provided with a longitudinally extending groove formed upon one side thereof, and upon their opposite sides said points taper to longitudinally extending cutting edges.

100 3. A pick, comprising a stem, a point integral with said stem, said point substantially V-shaped in cross-section and provided with a longitudinally-extending cutting edge, and said point provided with a longitudinally-extending groove formed in the side opposite to its cutting edge.

105 4. A pick, comprising a stem, a point se-

cured to said stem, said point provided with a cutting edge upon one side and with a groove upon the side opposite to said cutting edge.

5. As a new article of manufacture, a mining or cutting pick, comprising a stem, provided with a central and side points, the central point of greater length than the side points, and each point tapering from the stem throughout its entire length to its forward end.

6. As a new article of manufacture, a pick, comprising a stem provided with a central and side points, the central point of greater length than the side points, and each point provided with a cutting edge upon the same side, and the cutting edges extending throughout the entire length of all of said points.

7. A mining pick, comprising a stem, a

central and side points secured to said stem, 20 each point tapering from a broad back downwardly to a longitudinally-extending cutting edge, and the central point of greater length than and positioned in a horizontal plane below the side points.

8. A pick, comprising a stem, a series of points integral with said stem, each point tapering from a broad back to a lower cutting edge, the cutting edges of all of the points formed on the same side, and one of the 30 points of greater length than the remaining points.

In testimony whereof I hereunto affix my signature in presence of two witnesses.

THOMAS N. WALLACE.
